UNITED STATES PATENT OFFICE

WILLIAM W. LASKER, OF BROOKLYN, NEW YORK, ASSIGNOR TO REMINGTON RAND INC., OF BUFFALO, NEW YORK, A CORPORATION OF DELAWARE

PERFORATING MACHINE

Application filed June 17, 1929. Serial No. 371,374.

This invention relates to card perforating machines in which a punch set-up is made for all the information to be punched before the punching operation takes place and in which provision is made for automatically erasing the set-up later in the cycle of operation of the machine.

The principal object of this invention is the provision of improved means for perforating two cards with the same information and for discharging the cards into separate card receptacles.

Another object of this invention is to employ electrical connections to control the machine to punch two cards according to one set-up and to discharge these cards into separate receptacles.

Still another object of this invention is the application of such mechanism to a machine of the type shown in Letters Patent of the United States #1,684,546 granted to me Sept. 18, 1928.

To the above and other ends which will hereinafter appear my invention consists in the features of construction, arrangements of parts and combinations of devices set forth in the following description and particularly pointed out in the appended claims.

Other objects will appear from the following description taken in connection with the accompanying drawings in which,

Fig. 1 is a front view of the machine showing a portion of the mechanism of the present invention applied thereto,

Fig. 2 is an end view of the same as seen from the right-hand in Fig. 1 and with parts broken away and in section,

Fig. 3 is a detail, fragmentary, perspective view which shows the carriage return switch and electrical connections,

Fig. 4 is a detail, fragmentary, perspective view which shows the "one" and "two" trip keys and contacts,

Fig. 5 is a detail, fragmentary, perspective view which shows the two card controlling mechanism controlled by the "two" trip key,

Fig. 6 is a detail, fragmentary, perspective view which shows portions of the card deflector and operating means therefor, and

Fig. 7 shows a diagram of the circuits controlling the one and two card operations.

The drawings disclose only so much of the old mechanism as is necessary for a clear understanding of the invention.

The keyboard 10 is generally the same as that shown in Letters Patent of the United States #1,684,001 granted to Weiland et al. Sept. 11, 1928, and comprises numeral and alphabet keys, and a "one" trip key 11 and a "two" trip key 12 which will be described hereinafter.

The numeral and alphabet keys when depressed make circuits as shown in the patent to Weiland et al. through solenoids in a housing 13 which operate the usual Bowden wires 14 to actuate levers 15 to set up set-bars for controlling perforating as is well understood. The levers 15 actuate a common bail or universal bar 16 to operate an escapement lever 17 to control the usual escapement pawls or dogs and permit the carriage 18 to be drawn one punch-hole column to the right by the usual spring drum 19 (Fig. 2) whenever any set-bar is depressed.

In earlier types of machines the carriage 18 was returned to the left to erase the set-up by a lever 20 (Fig. 1) which through a link 21 rocked the erasing lever 22 to bring the wiping roller 23 successively into contact with inclined faces of pawls 24 to swing said pawls and operate holding detents (not shown) to release the set-up set-bars.

In the machine shown in the Lasker patent this is accomplished automatically upon depression of a carriage return key or in an operating cycle initiated by a trip key and which includes a regular punching operation. As shown in this patent, this mechanism comprises a carriage return block 25 (Fig. 1) carrying a cam lug 26 for engagement with a roller 27 on the lever 20 for swinging the wiping roller into position to erase the set-up. Said mechanism also includes a carriage return lug 28 for engaging a projection 29 that is fixed to the carriage and extends forward of the lever 20 at the pivotal center thereof, such engagement of the projection 29 taking place after the lever 20 has been rocked by the cam 26 and re-

sulting in returning the carriage 18 to the left. The carriage return block 25 is moved to the right by the usual tape 85 and spring drum 86. The carriage is returned to the left by a ring magnet 30 connected to the other end of the tape 85, and adapted to be energized to travel with a sleeve 31 on a main shaft 32. The sleeve 31 is driven from a motor which also drives a generator to supply current of the proper voltage to the electrical circuits of the machine.

The circuit through the ring magnet 30 (Fig. 3) is controlled by a magnet 35, energized as later described, which operates a retaining lever 36 for a double knife switch carrying lever 37 connected to a spring drawn slide 38 which is normally urged to the right by a spring 39 and is returned to the left as the carriage is returned home as shown in the patent to Lasker. When the lever 36 is released it makes a circuit through the magnet 30 to cause the same to be rotated by the sleeve 31 to return the carriage to the left.

25 The main shaft 32 is driven from the sleeve 31 by a clutch mechanism 40 (Fig. 1) one member 41 of which is spring urged to press its clutch facing into engagement with a flange 42 on the sleeve 31, and is released for such movement by a stopping pawl 43 moved into released position by a magnet 44 (Fig. 7) in circuit with parts later referred to. The clutch mechanism is not claimed herein and may for the purposes of this invention be of any approved form as long as it may be controlled from the magnet 44.

The machine may be released for a single operation by depressing the one trip key 11 (Figs. 1, 4 and 7). When this key is depressed with the double knife switch 46 (Figs. 1 and 7) in the position "a" of Fig. 7, a circuit will be closed through the trip magnet 44 and the double knife switch 37 which is normally in the position shown in these figures. The energization of the trip magnet 44 releases the clutch member 41 to frictionally engage the flange 42 on the sleeve 31. This causes the machine to make one cycle of operation. During this operation a conducting bar 48 (Fig. 5) on an insulator cylinder 49 on the main shaft 32 will bridge spaced spring contacts 50 and 51 closing the circuit through the carriage return magnet 35 which permits the double knife carriage return switch on the lever 37 to close the circuit through the ring magnet 30 and cause the return of the carriage.

60 The "two" trip key 12 (Figs. 1, 4 and 7) closes the circuit through a special trip magnet 52 (Figs. 1, 2, 5 and 7) which raises a slide 53 mounted on a bracket plate 54 suitably secured to the machine. This slide is raised against a spring 55 stretched between a pin 56 on the slide and a pin 57 on an arm 58 formed with a yoke hub 59 pivoted on a

stud 60 projecting from the bracket plate 54. As the slide is lifted it raises a link 61 mounted at one end on the pin 56 and pivoted at its other end to an ear 62 on the plate 54, to disengage its notch 63 from the pin 57 (Fig. 5) on the arm 58 thus permitting this arm and the yoke hub connected therewith to be rocked counter-clockwise by the spring 55. The yoke hub 59 of the arm 58 carries the carriage return spring switch arms 50 and 51 and a trip spring switch arm 64 and when rocked counter-clockwise as indicated above moves the arms 50 and 51 away from the cylinder 49 and prevents the bar 48 thereon from completing the circuit through the return magnet as the main shaft is rotated. The switch arms 50 and 64 in their moved position close the circuit through electrically connected spring arms 65 and 66 on a stud 67 on the bracket plate 54 (Figs. 5 and 7) which maintains the trip circuit energized and the machine in operation until this condition is changed. The switch arms 50, 51 and 64 and the circuits they control are shown in Fig. 7.

20 The upper end of the arm 58 is connected by a link 70 to an arm 71 secured to a rock shaft 72 (Figs. 2 and 6) carrying a deflector 73. Normally when the machine perforates but one card for a set-up, the deflector is in the full line position shown in Fig. 2 so that all of these cards will be deflected into the rear pocket 74. When the two trip key 12 is depressed and the arm 58 is rocked counter-clockwise, the deflector will be moved to the dotted line position directing the first card into the front pocket 75.

25 The arm 58 is restored to its home position during the second cycle of operation by a cam 80 (Fig. 5) rotatable on the stud 67 and connected to a gear 81 meshing with a pinion 82 secured to a larger gear 83 in mesh with a small gear 84 on the main shaft 32. The gear reduction is two to one so that the cam makes one-half cycle while the machine 110 makes one operation. The cam is shown in the position it would occupy at the end of the first cycle if the two trip key had been depressed with the cam in the home position. On the second cycle of operation the cam will 115 restore the arm 58 thereby breaking the circuit through the trip magnet 44 and allowing the machine to come to rest at the end of that cycle. At the same time this restoration of the arm 58 places the spring switch arms 50 and 51 against the cylinder 49 to be bridged by the bar 48 to complete the circuit through the carriage return magnet. The carriage is returned and the set-up erased 120 ready for another set-up.

30 Repeated operations of any desired number may be made by swinging the double knife switch 46 to the position "b" in Fig. 7. This closes the circuit through the regular 125

trip magnet and breaks the carriage return circuit at this point.

Operation

- 5 One card operations are made by pressing the "one" trip key 11. An indeterminate number of operations is made by throwing the switch 46 from "a" to "b", Fig. 7. A two card operation is effected by pressing the two trip key 12 starting of course with the restoring cam 80 in home position. Depression of the "two" trip key 12 energizes the special trip magnet 52 which swings the spring contact arms 50 and 51 away from the cylinder 15 49 to prevent the bar 48 from closing the circuit through the carriage return magnet 30. The arm 50 and the trip magnet switch arm 64 are brought into electrical connection by spring contact arms 65 and 66 which establishes a circuit through the trip magnet 44. This condition is maintained until the cam 80 restores the arm 58 and the contacts 50, 51 and 64, placing the contacts 50 and 51 in position to be bridged by bar 48 to cause return of the carriage and an erasing of the set-up just before the end of the second cycle of operation. By this mechanism, the machine is controlled to punch two cards for the same set-up, the first card being delivered 20 into the front pocket 75 and the second card into the rear pocket 74.

What I claim as new and desire to secure by Letters Patent, is:

- 25 1. In a machine of the class described comprising punch set-up mechanism, punching mechanism, set-up erasing mechanism, electrical contact means for causing functioning of said set-up erasing mechanism automatically subsequently to effecting punching; the combination therewith of key controlled electric means for moving said contact means out of contact making position, and means operated by the machine to automatically restore said contact means to functioning position during the second cycle of operation of the machine.
- 40 2. In a machine of the class described comprising punch set-up mechanism, punching mechanism, set-up erasing mechanism, electrical contact means for causing functioning of said set-up erasing mechanism automatically subsequently to effecting punching; key controlled electric means for moving said contact means out of contact making position and to cause the machine to make a plurality of operations, and means operated by the machine to automatically restore said contact means to cause an operation of the erasing means and discontinuation of operation of the machine at the end of said plurality of operations.
- 45 3. In a perforating machine comprising punch controlling set-up means, means for effecting a punching operation, a main operating shaft, an erasing means for the set-
up means, an electrical contact bar movable with the main shaft, movable contacts in circuit with the erasing means adapted to be bridged by said contact bar toward the end of a cycle of operation for erasing said set-up; a key for causing the machine to operate and for moving said movable contacts out of contact making position, a third movable contact movable with said movable contacts, a circuit for causing a plurality of operations of machine closed by one of said first movable contacts and said third movable contact, and means operated by the machine for moving all of said movable contacts into home position during the last of said plurality of operations of the machine.
- 50 4. In a perforating machine comprising punch controlling set-up means, means for effecting a punching operation, a main operating shaft, an erasing means for the set-up means, an electrical contact bar movable with the main shaft, movable contacts in circuit with the erasing means adapted to be bridged by said contact bar toward the end of a cycle of operation for erasing said set-up; a key for causing the machine to operate and for moving said movable contacts out of contact making position, a third movable contact movable with said movable contacts, a circuit for causing a plurality of operations of machine closed by one of said first movable contacts and said third movable contact, and means operated by the machine for moving all of said movable contacts into home position during the last of said plurality of operations of the machine.
- 55 5. In a card punching machine, the combination of a gang of punches, punch set-up mechanism for selectively rendering said punches effective including a carriage that receives a step-by-step movement in one direction and a return movement to initial position in the opposite direction and that carries actuating members for effecting a set-up, an erasing device carried by said carriage and operative on the return of the carriage to erase the set-up, automatically operating means including a key for returning said carriage and causing the set-up to be erased after a single punching operation has been effected, and means including a second key for rendering said returning means and erasing device operative only after a predetermined plurality of punching operations has taken place.
- 60 6. In a perforating machine the combination of a series of punches, set-up mechanism for selectively rendering said punches effective and including a carriage that receives a step-by-step feed in one direction and a return movement to the initial position in the opposite direction, control means for operating the machine to produce a punched record from said punches in accordance with the

- set-up of said set-up mechanism, power actuated automatically operating means for returning said carriage to its initial position in timed relation to the punching operation 5 and after the record has been produced, and means including a key for preventing the automatic return of the carriage by said last mentioned means until a plurality of punching operations has been effected.
- 10 7. In a perforating machine, the combination of a series of punches, a series of settable devices for controlling said punches, a traveling carriage, means on said carriage for setting said settable devices, a normally inoperative erasing device, power operated means for returning said carriage to initial position, means for automatically rendering said erasing device operative to restore said settable devices during the return of the carriage, means including a key for automatically causing a return of the carriage after a single punching operation only has been effected, and means including a separate key for causing an automatic return of the carriage only after a predetermined plurality of punching operations has been effected.
- 15 8. In a perforating machine, the combination of a series of punches; means for selectively determining the punches to be rendered effective and the positions on the card where perforations are to be made therein, said means including a carriage that receives a step-by-step movement in one direction and a return movement to its initial position; means for effecting a punching operation; power actuated automatically operating means for returning said carriage to initial position in timed relation to the punching operation and after the card has been punched; automatically operating means for restoring elements of the selective determining means to normal position during the return movement of the carriage; and means including a key for preventing a return of the carriage and a restoration of said elements of the selective determining means to normal position until a given plurality of punching operations has taken place.
- 20 9. In a card punching machine, the combination of a gang of punches, punch set-up mechanism for selectively rendering said punches effective including a carriage that receives a step-by-step movement in one direction and a return movement to initial position in the opposite direction and that carries actuating members for effecting a set-up, an erasing device carried by said carriage and operative on the return movement of the carriage to erase the set-up, automatically operating means for returning said carriage and causing the set-up to be erased after a single punching operation has been effected, said last mentioned means including a key, electrical contacts controlled by said key, means controlled by said electrical contacts for setting the machine in operation after the set-up has been completed and causing a cycle of operations to be effected including an automatic restoration of the carriage and an erasing of the set-up after a single card has been punched; a second key; electric contacts controlled thereby; and means controlled by said last mentioned contacts for enabling a plurality of cycles of the machine to be effected to punch a plurality of cards before the carriage is automatically returned and an erasing of the set-up is effected.
- 25 10. In a card punching machine, the combination of a gang of punches, punch set-up mechanism for selectively rendering said punches effective including a carriage that receives a step-by-step movement in one direction and a return movement to initial position in the opposite direction and that carries actuating members for effecting a set-up, an erasing device carried by said carriage and operative on the return movement of the carriage to erase the set-up, automatically operating means for returning said carriage and causing the set-up to be erased after a single punching operation has been effected, said last mentioned means including a key, electrical contacts controlled by said key, means controlled by said electrical contacts for setting the machine in operation after the set-up has been completed and causing a cycle of operations to be effected including an automatic restoration of the carriage and an erasing of the set-up after a single card has been punched; a second key; electric contacts controlled thereby; and means controlled by said last mentioned contacts for enabling a plurality of cycles of the machine to be effected to punch a plurality of cards before the carriage is automatically returned and an erasing of the set-up is effected.
- 30 11. In a card punching machine, the combination of a gang of punches; punch set-up mechanism for selectively rendering said punches effective including a carriage that receives a step-by-step movement in one direction and a return movement to initial position in the opposite direction and that carries actuating members for effecting a set-up; an erasing device carried by said carriage and operative on the return movement of the carriage to erase the set-up; automatically operating means for returning the said carriage and causing the set-up to be erased after a single punching operation has been effected, said last mentioned means including a key, electrical contacts controlled by said key, means controlled by said electrical contacts for setting the machine in operation after the set-up has been completed and causing a cycle of operations to be effected including an automatic restoration of the carriage and an erasing of the set-up after a single card has been punched; a second key; electric contacts controlled thereby; and means controlled by said last mentioned contacts for enabling a plurality of cycles of the machine to be effected to punch a plurality of cards before the carriage is automatically returned and an erasing of the set-up is effected.
- 35 12. In a card punching machine, the combination of a gang of punches; punch set-up mechanism for selectively rendering the punches effective including a carriage that receives a step-by-step movement in one direction and a return movement to initial position in the opposite direction; erasing means

carried by said carriage and operative on the return of the carriage to erase the set-up; and selectively operable means for automatically returning said carriage and causing said erasing means to function, the last recited means including means for causing the carriage to return and the set-up to be erased after each punching operation, means for causing the carriage to return and the set-up to be erased only after a given plurality of punching operations, and means to cause an indefinite number of punching operations without a return of the carriage and without erasing the set-up.

Signed at Brooklyn in the county of Kings and State of New York this 13 day of June, 1929.

WILLIAM W. LASKER.

13. In a card punching machine, the combination of a gang of punches; punch set-up mechanism for selectively rendering said punches effective including a carriage that receives a step-by-step movement in one direction and a return movement to initial position in the opposite direction; erasing means carried by said carriage and operative on the return of the carriage to erase the set-up; and electro-mechanical means for returning said carriage and causing said erasing means to function automatically after each punching operation or only after a given plurality of punching operations has taken place, or to remain continuously quiescent and ineffective after an indefinite number of punching operations has been effected as may be desired, said electro-mechanical means including a contact-controlling key, means controlled by an actuation thereof for starting the machine and for causing an erasing of the set-up after a single punching operation, a second contact-controlling key, means controlled thereby for starting the machine and erasing the set-up after a given plurality of punching operations has taken place, and a switch by which the means for returning the carriage and controlling the erasing of the set-up remain ineffective indefinitely so that an indefinite number of cards may be punched from the same set-up.

14. In a card punching machine, the combination of a gang of punches, a keyboard, set-up mechanism controlled by the keys in said keyboard for selectively determining which of the punches of said gang are to be rendered effective, electro-mechanical means normally operable for automatically erasing said set-up mechanism after each punching operation and including cooperative electrical contacts normally brought into cooperation after each punching operation to bring about an operation of said erasing means, and key controlled electro-mechanical means for starting the machine and shifting one of said contacts out of cooperative relation with another until after a given plurality of punching operations has been effected, thereby rendering the erasing means ineffective.

until after a given plurality of punching operations has taken place and a given plurality of cards has been punched from the same set-up.
